UNITED STATES PATENT OFFICE.

LAWRENCE MERLE RICKETTS, OF BALTIMORE, MARYLAND, ASSIGNOR OF ONE-HALF
TO WALTER A. HARMAN, OF BALTIMORE, MARYLAND.

STEEL WHEEL.

1,352,146.

Specification of Letters Patent. Patented Sept. 7, 1920.

Application filed August 23, 1919. Serial No. 319,365.

To all whom it may concern:

Be it known that I, LAWRENCE M. RICKETTS, a citizen of the United States, and resident of Baltimore, Maryland, have invented certain new and useful Improvements in Steel Wheels, of which the following is a specification.

My invention relates to wheels of the pressed steel type and it consists in the features and combination of parts hereinafter described and particularly pointed out in the claims.

In the accompanying drawings—

Figure 1 is a sectional view of the wheel. 15 Fig. 2 is a side elevation of a portion of the wheel.

Fig. 2^a is a detail.

Fig. 3 is a sectional view of the hub with a portion of the wheel in place thereon.

20 Fig. 4 represents a portion of the wheel and a coacting portion of the hub.

Fig. 5 is a face view looking at the parts of Fig. 4 from the right hand side thereof.

Fig. 6 is a detail view of a portion of the 25 hub, and

Fig. 7 is a detail view of a portion of the shell.

Fig. 8 shows in two views a split locking washer.

30 In Fig. 1, 8 indicates the body of the wheel which is formed of sheet metal, this body portion consisting of an annular portion arranged in a plane substantially at right angles to the axis of the wheel and a portion 9 continuous with the portion 8 but extending at an angle laterally from the plane of the portion 8, this annular portion being curved at 10 and merging into an overhanging rim portion 11 which is arranged substantially centrally over the annular body part 8 and is provided with a flange 12 at its terminal edge.

The edge of the rim 11 opposite to the edge at which the flange 12 is located is 45 devoid of a flange and this enables a demountable rim and tire 13 to be slipped into place and held by clips 14 which are retained by bolts 15 passing through the angular extension of the annular body portion 50 8. The body portion 8 is formed continuously with spokes 16 and 17. These spokes are cut from the body of the metal and one series 16 extends to the right in Fig. 1 and the other series extends to the left and these 55 spokes alternate with each other and their

lower ends are connected with the right hand and left hand ends of the hub or shell 18 by any suitable means such as by the rivets 19. The arrangement is such that the rim of the wheel is substantially over the larger inner 60 end of the hub. In Fig. 1 the spokes 17 are in a plane substantially at right angles to the axis of the wheel though these spokes 17 may be inclined to a sharper degree than illustrated in said Fig. 1.

65 In Fig. 3 I show the wheel shell or center 18' mounted on the hub 20 so as to turn with said hub as one body therewith. For this purpose the shell is provided with a notch or cut out portion 21 which fits over a 70 fillet 22 on the hub 20 adjacent the flange 23. The outer end of the shell 18' is provided with an inwardly extending projection 24 which fits into a notch 25 in the hub 20 and thus the shell 18' is held against circumferential movement in relation to the hub 20. The shell 18' is held against axial displacement in relation to the hub by a nut 26 which has a base or flange portion 27 lying over the end of the shell 18' and restraining it against 75 axial displacement. The nut 26 is screw threaded at 28 into the end of the hub 20. Roller bearings are provided at 29 between the hub and the axle 30.

80 In manufacturing these wheels it may be 85 found after assembling the wheel on the hub that there is a slight eccentricity of the edge of the rim in relation to the center of rotation. In order to compensate for this the rim is initially provided with extended projections indicated in Fig. 2^a and if the eccentricity is found to exist the wheel then 90 will be mounted on a mandrel and these projections ground down to a common diameter which will insure the wheel being concentric.

95 In Fig. 8 I show a split locking washer which fits between the threaded section of the nut and a shoulder on the hub as indicated at α in Fig. 3.

100 I claim as my invention:

1. A steel wheel having an annular body portion near its rim lying at its inner part in a plane substantially at right angles to the wheel axis and at its outer part at an 105 angle extending to one side of the said plane, said body portion merging into an overhanging rim at the extreme outer edge thereof, the center of said rim lying over the inner part of said body and substantially cen- 110

trally in relation thereto, said rim being flanged at its inner edge, the outer edge of said rim being flangeless, and means for holding a tire demountably on said rim, 5 substantially as described.

2. A steel wheel having an annular body portion lying substantially in a plane at right angles to the axis of the wheel, a rim portion overhanging the body portion and 10 connected therewith by a continuation of

said body portion extending at an angle from the body portion and merging into the outer edge of the rim, and spokes integral with the body portion and arranged in two series the members of which alternate with each 15 other and diverge in respect to each other, and a shell connecting with the inner ends of the spokes, substantially as described.

In testimony whereof I affix my signature.

LAWRENCE MERLE RICKETTS.
